UNITED STATES PATENT OFFICE.

LOUIS McMURRAY, OF BALTIMORE, MARYLAND.

APPARATUS FOR ELECTROPLATING.

SPECIFICATION forming part of Letters Patent No. 393,170, dated November 20, 1888.

Application filed March 1, 1887. Serial No. 229,270. (No model.)

To all whom it may concern:

Be it known that I, LOUIS McMURRAY, of the city of Baltimore and State of Maryland, have invented certain new and useful Improvements in Apparatuses for Electroplating, of which the following is a full description.

The accompanying drawings illustrate the apparatus, of which—

Figure 1 is a perspective view of the apparatus with bath at one end and drying device at the other; Fig. 2, a longitudinal sectional view showing interior of the electroplating apparatus. Fig. 3 is a view of the anodes, which lie at the bottom of the box containing the solution. Fig. 4 is a side elevation of the electroplating apparatus, showing the endless carrier and the cans entering and leaving the solution. Fig. 5 is a plan or top view of the electroplating apparatus.

The object of the invention, primarily, is for the purpose of electroplating metallic cans, such as are well known in the market as containing provisions or alimentary substances, and electroplating the exterior thereof after the same have been filled, sealed, and processed; but the apparatus may be used equally well for plating articles of any form or shape, and the description of the apparatus and its mode of operation contemplates the device as employed to electroplate such cans, but it may be readily used for plating other things adapted to be coated.

The cans are first polished, and an apparatus for polishing them is described in an application for Letters Patent of even date herewith, and when so polished they are placed in the bath-tub A, to the left, and from thence placed upon a carrier which carries them through the electroplating-solution, and are thence delivered to the drying device on the right.

B is a frame-work, which supports a water-tight box, B'. Within this box is placed a solution of the metal with which it is designed to plate the can or other article. This solution is prepared in the ordinary way, and may be of gold, silver, nickel, or other electroplating-solution as known and used in the trade. The surface-line of the solution is indicated at b, Fig. 2. Two binding-posts are shown in the drawings, Fig. 2, marked + and -, re-

spectively, which lead to and form a circuit through a battery or dynamo. (Not shown in the drawings.) The side walls of the box B' have upon their upper edges a strip of metal or other conducting material connected with the + binding-post. Across the top of the box and upon these conductors are laid the metal rods b², to which are suspended the electrodes marked + of the material of which the plating is to be made, so as to hang within the solution. At the bottom of the solution, also within the box, are laid other positive electrodes, also marked +, and composed of the same material. These positive electrodes are connected together and lead to the positive pole of the battery or dynamo. They may be laid in rows, if desired, and as many as are necessary. The electrodes marked + are the anodes. Within the box, upon or near its side walls, are constructed the tracks b⁴. These tracks are made of metal or other good conducting material and are connected with the negative pole of the battery. They serve the double purpose of conductor, and at the same time guides to direct the carrier (hereinafter described) and are located at a suitable place between the top and bottom positive electrodes.

Upon a suitable part of the frame-work of the apparatus is journaled the shaft C, which carries the driving-pulley c¹, operated by the belt c². The shaft C also carries a sprocket-wheel, around which is placed the chain c³. Upon another shaft, c⁴, suitably journaled, is a sprocket-wheel, c⁵, of larger diameter than that on the shaft C, and this sprocket-wheel is driven by the chain c³. Another sprocket-wheel upon the shaft c⁴ drives the sprocket-wheel c⁶ on the shaft c⁷. This latter is journaled in the frame-work and runs across the end of the machine. It also carries sprocket-wheels which mesh with and operate an endless-chain carrier, D. The arrangement of shafts C c⁴ c⁷ are for the purpose of giving a slow motion to the carrier D. Any other arrangement which accomplishes this purpose would answer as well.

The carrier D is composed of chains, two or more, to the links of which are secured cross-wise of the machine plates or strips of conducting material d. The lengths of these plates

or strips are adjusted, so that their ends will enter the track b^4 and be guided thereby in passing through the solution. As this track b^4 is in connection with the negative pole of the 5 battery it follows that these cross-strips are also in connection therewith, as they are in contact with the track from the time they enter the solution until they pass out at the other end. Secured to these strips and perpendicular

10 thereto are the upright pieces d' , which may be made firm by the braces d'' . The cans to be plated are placed upon the carrier in rows between the uprights d' . As movement is imparted to the carrier the cans move with it and 15 are kept in place by those uprights. It follows from this description that the plates of material from which the deposit is made—marked + in the drawings—form the anodes and the cans to be plated the cathodes. The 20 cans filled with the provisions have usually a specific gravity about or nearly equal to that of the solution, and might be easily disturbed or floated. I have therefore provided a means for keeping them in position and in contact 25 with the cross-strips.

Upon suitable uprights, b^5 , attached to the frame-work of the machine, are placed the cross-bars b^6 . From these cross-bars are suspended the small rods or wires b^7 . To the lower end 30 of these rods or arms are attached the tubes E , made of rubber or other pliable material which will not injure the cans. These tubes are filled with shot to sink them and cause them to bear upon the cans as they pass through the solution. The cans are thus kept, without injury 35 to their surfaces, in contact with the carrier, and as they pass they receive the deposit from the solution and become well coated in passing. From this carrier they are delivered into 40 the sawdust-box F , where they are dried.

What I claim, and desire to secure by Letters Patent, is—

1. In an electroplating apparatus, a box con-

taining an electroplating solution, in combination with an endless conveyer arranged to 45 pass horizontally through the solution, and provided on its upper side with supports for holding loosely the article to be plated, means for imparting movement to the conveyer through the solution, and means for connecting the conveyer and article to be plated with an electrical generator.

2. In an electroplating apparatus, a box containing a solution of an electroplating material, in combination with an endless conveyer 55 consisting of one or more linked chains, the conveyer arranged to pass horizontally through the liquid, and provided on its upper side with supports, as d' , secured to the links of the conveyer, means for imparting motion to the conveyer through the solution, and means for connecting the conveyer and article to be plated with an electrical generator.

3. In an electroplating apparatus, a box containing a solution of an electroplating material, 65 an anode of the same material immersed in the solution, and connected with an electrical generator, in combination with an endless conveyer, means for retaining a free or detached cathode upon the conveyer, and means 70 for connecting the cathode and conveyer with an electrical generator.

4. In an electroplating apparatus, a box containing a solution of an electroplating material, in combination with an endless conveyer, 75 means for moving the conveyer through the solution, means supported in the solution above the conveyer to hold the article to be plated in contact with the conveyer, and means for connecting the conveyer with an electrical 80 generator.

LOUIS McMURRAY.
